UNITED STATES PATENT OFFICE.

W. MAX REID, OF AMSTERDAM, NEW YORK.

DESIGN FOR A BURIAL-CASKET.

SPECIFICATION forming part of Design No. 12,256, dated May 10, 1881.

Application filed March 29, 1881. Term of patent 3½ years.

To all whom it may concern:

Be it known that I, W. MAX REID, of Amsterdam, in the county Montgomery and State of New York, have invented a Design for a 5 Burial-Casket, of which the following is a specification.

The nature of my design is fully represented in the accompanying illustration, to which reference is made.

10 The illustration represents a burial-casket covered with cloth or velvet, and with satin rays.

My design relates to the ornamentation or peculiar manner of raying the blinds, sides, ends, and corners, substantially as shown in 15 the accompanying illustration.

The surface not covered with rays may be either plain or tufted.

What I claim as my invention is—15 The design for a burial-casket having the blinds, sides, ends, and corners rayed and ornamented as described, and shown by the accompanying illustration.

W. MAX REID.
